UNITED STATES PATENT OFFICE.

OBADIAH SEELY, OF SYRACUSE, NEW YORK.

DESIGN FOR A DOOR-HINGE.

SPECIFICATION forming part of Design No. 18,828, dated December 25, 1888.

Application filed November 18, 1888. Serial No. 291,041. Term of patent 3½ years.

To all whom it may concern:

Be it known that I, OBADIAH SEELY, a citizen of the United States, residing at Syracuse, in the county of Onondaga and State of New York, have invented and produced a new and original Design for a Door-Hinge, of which the following is a specification, reference being had to the accompanying drawing, forming part hereof, in which I show a plan view of a hinge as an illustration of my design.

The leading features of my design consist of the raised embossed-like surface of the scroll and curve work upon a plain background having scroll ends.

In the drawing, A represents the background, provided with curved ends or scrolls or imitations of scrolls, 1, 2, and upon this plain background and integral therewith I create the scrolls or imitations of scrolls 3, 4, the one curving in a reverse direction to the other and uniting at substantially the center of the hinge-leaf with a substantially-acute angle, 5, on the outer surface, and substan-

tially a triangular point, 6, reaching nearly, if not quite, to the barrel and pintle of the hinge. 25 I also insert a filling, 8, of angular form, in the angle 5, either flush with the scroll-work or partially flush with it, or wholly or partially flush with the background. I also leave spaces 7 between the background and scrolls, open 30 entirely through or depressed or concaved to simulate an opening.

What I claim as my invention and design is—

The design for a hinge-leaf, comprising a 35 plain background and scrolls mounted thereon curving in reverse directions from the center and there united, forming an angle between the scrolls and upon the outer end of the hinge-leaf, as shown. 40

In witness whereof I have hereunto set my hand this 26th day of October, 1888.

OBADIAH SEELY.

In presence of—

H. P. DENISON,
C. W. SMITH.
